UNITED STATES PATENT OFFICE

111,501

DESIGN FOR A SUN CHAISE

Arthur Wesley, Chicago, Ill., assignor to Burton-Dixie Corporation, Chicago, Ill., a corporation of Delaware

Application February 4, 1938, Serial No. 74,866

Term of patent 7 years

To all whom it may concern:

Be it known that I, Arthur Wesley, a citizen of the United States, residing at Chicago, in the county of Cook and State of Illinois, have invented a new, original, and ornamental Design for Sun Chaises, of which the following is a specification, reference being had to the accompanying drawing, forming part thereof.

The figure is a perspective view of a sun chaise showing my new design.

I claim:

The ornamental design for a sun chaise, as shown.

ARTHUR WESLEY.
